US00D605663S

(12) **United States Design Patent**
Hopper

(10) **Patent No.:** **US D605,663 S**
(45) **Date of Patent:** **** Dec. 8, 2009**

(54) **HIGH VOLUME LOW PRESSURE SPRAY PUMP**

D585,460 S * 1/2009 Plunk et al. D15/9

(75) Inventor: **Timothy George Hopper**, Surrey (GB)

* cited by examiner

(73) Assignee: **Earlex Limited**, Guildford, Surrey (GB)

Primary Examiner—R. Seifert

(**) Term: **14 Years**

(74) *Attorney, Agent, or Firm*—Alfred A. Fressola; Ware, Fressola, Van Der Sluys & Adolphson LLP

(21) Appl. No.: **29/291,914**

(57) **CLAIM**

(22) Filed: **Sep. 19, 2007**

The ornamental design for the high volume low pressure spray pump, as shown and described.

(51) **LOC (9) Cl.** **15-01**

DESCRIPTION

(52) **U.S. Cl.** **D15/7**

FIG. 1 is a isometric view of the high volume low pressure spray pump showing my new design;

(58) **Field of Classification Search** D15/7-9;
